ARLAND A. DECKER, OF STOCKTON, CALIFORNIA

BANJO VIBRATOR

Application filed November 20, 1928. Serial No. 320,571.

This invention relates to stringed instruments and particularly to a device for vibrating the strings of a banjo and which is especially of value in producing different sound effects when the banjo is used in solo work.

The principal object of my invention is to provide a device for the purpose adapted to be actuated by the same hand employed to manipulate or strike the strings, and which is so constructed and arranged that the strings will be caused to vibrate in unison and without being muted; and so that the vibrations take place on both sides of the pitch, thereby causing the vibratory sounds to retain the proper full tones of the instrument.

A further object is to arrange the actuating member of the device so that it may be thrown back out of the way when its use is not desired, without actually removing said device from the instrument, and without affecting the pitch to which the instrument was previously tuned.

Another object is to construct the device in the form of an attachment which may be readily applied to any standard banjo.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views.

Fig. 1 is a fragmentary perspective view of a banjo showing my vibrating attachment mounted in operative position thereon.

Fig. 2 is a longitudinal section of the attachment showing the actuating member in its operative but slack position.

Fig. 3 is a similar view showing the actuating member in a fully depressed position.

Fig. 4 is a similar view showing the actuating member as thrown back and out of the way.

Referring now more particularly to the characters of reference on the drawings, the

numeral 1 denotes the cylindrical tone chamber of the banjo on the lower end of which is secured the tail-piece structure 2 of any standard form, which is supported as usual by a bolt 3 mounted in a block 4 projecting outwardly from the chamber. The strings 5 are attached at one end to the tail-piece and then extend from said tail-piece over the bridge 6 which is mounted on the head 7; said strings from the tail-piece to the bridge being in clearance relation to the head.

My vibrator attachment which is applied to such standard arrangement of parts comprises a rigid frame which consists of a pair of inverted L-shaped arms 8 having transversely shaped horizontal portions extending over the head toward the bridge and disposed parallel to the strings to the sides of the same; and a cross bar 9 connecting the outer lower ends of the arms and secured to the tail-piece structure by suitable means. The horizontal portions of the arms serve as supports for a pair of transverse pins 10 and 11, spaced lengthwise of the arms and disposed above the strings at right angles to the length thereof. The pin 10 serves as a hinge or pivot support for a plate 12 which extends from said pin toward the bridge and rests adjacent its forward end on all the strings simultaneously. The pin 11 forms the hinge or pivot for the actuating plate 13, which extends over the forward portion of the plate 12 to a termination some distance in front of the same but short of the bridge. This plate is of stiff spring metal and adjacent its hinged end is formed with a flat angular bend as shown at 14. The included angle of this bend faces uppermost when the plate is in said above named or operative position, so that the forward portion of the plate has an upward slant relative to the plate 12 and at the peak of the bend bears against said plate 12 for the full width thereof.

By means of this arrangement therefore it will be seen that downward vibrations imparted to the actuating plate by the hand of the operator will cause the strings to be alternately tightened and slackened, thus of course imparting vibration to said strings with the desired tone effects. The under plate

12 is to prevent damage to the strings which might otherwise be had if they were directly engaged by the relatively sharp edge of the bend of the actuating plate.

5. The sleeve 15 which is formed with the plate 13 and which turns on the pin 11 is formed with a raised cam portion C so positioned as to engage and depress the plate 12 slightly (thereby causing the strings to be also depressed and tightened) only when the plate 13 is swung away from its forward position to face toward the tail-piece and is depressed as far as possible in that position, as shown in Fig. 4. The strings are tuned 15 to the desired pitch when the plates are in this position, so that when the plate 13 is swung forwardly to an operative but a slack position the strings will be slacked somewhat and the tone correspondingly flat. This flatness however is overcome when the instrument is then placed by the normal pressure of the hand of the player on the actuating plate, which causes the strings to be depressed and tightened sufficiently to restore 20 the tension to that at which the proper tuning pitch is obtained. The advantage of having the strings relatively slack when the actuating plate is released from any pressure is that when said plate is alternately depressed and released by the vibratory movement of the hand at the same time the strings are being struck; the resulting vertical vibrations thus imparted to the springs take place on both sides of the actual pitch of said strings so that the vibratory sounds have the 25 full proper tone of the instrument.

It is also to be noted that the cam C, when the plate 13 is depressed toward the tail-piece as far as possible, as shown in Fig. 4, besides depressing the plate 12 as previously stated, is then past a dead-center position with respect to the position of said plate 13. The latter is therefore held against undesired retractive movement or in such a manner that the tension of the strings cannot act to release the cam and swing the plate forwardly.

From the foregoing description it will be readily seen that I have produced such a device as substantially fulfills the objects of the invention as set forth herein.

While this specification sets forth in detail the present and preferred construction of the device, still in practice such deviations may be resorted to as do not form a departure from the spirit of the invention, as defined by the appended claims.

Having thus described my invention what I claim as new and useful and desire to secure by Letters Patent is:

60. 1. A device for vibrating banjo strings comprising a depressible plate to engage all the strings of the instrument simultaneously at a point between the tail-piece and bridge of the instrument, means for supporting said plate at one end in connection with the in-

strument, a separate actuating plate swivelly supported in superimposed relation to the first named plate and adapted at a certain point only in its length to be engaged with said first named plate.

70. 2. A device for vibrating banjo strings comprising rigid arms to extend to the sides of and above the plane of the strings from the tail-piece end thereof toward the bridge, means for mounting said arms in rigid position, a plate swivelly supported between the arms and resting on all the strings simultaneously, and a separate actuating plate swivelly supported between the arms in superimposed relation to the first named plate and adapted to extend beyond the forward end of the same and toward the bridge of the instrument; said actuating plate being formed intermediate its ends with a bend, the angle of which, when the plate is in said above named position, faces upwardly and so that the forward portions of the plate has an upward slope relative to the strings, the bend being so located as to engage the plate below intermediate the ends.

75. 3. A device for vibrating banjo strings comprising a depressible plate to engage all the strings of the instrument simultaneously at a point between the tail-piece and bridge of the instrument, means for supporting said plate at one end in connection with the instrument, a separate actuating plate swivelly supported in superimposed relation to the first named plate and adapted to be swung either forward to face toward the bridge of the instrument and to then engage the plate below, or in the opposite direction to face the 80 tail-piece of the instrument.

85. 4. A device for vibrating banjo strings comprising a depressible plate to engage all the strings of the instrument simultaneously at a point between the tail-piece and bridge of the instrument, means for supporting said plate at one end in connection with the instrument, a separate actuating plate swivelly supported in superimposed relation to the first named plate and adapted to be swung either forward to face toward the bridge of the instrument and to then engage the plate below, or in the opposite direction to face the 90 tail-piece of the instrument, and means provided with said actuating plate for causing the first named plate to be depressed to a predetermined extent when the actuating plate is in said last named position.

95. 5. A device for vibrating banjo strings comprising rigid arms to extend to the sides of and above the plane of the strings from the tail-piece end thereof toward the bridge, means for mounting said arms in rigid position, a pair of pins extending between and supported by the arms above the strings and spaced apart longitudinally of the arms, a plate mounted at one end on the pin nearest the tail-piece of the instrument and project- 100

ing toward the bridge thereof, said plate resting on the strings, and an actuating plate turnably mounted on the other pin and adapted to also project toward the bridge, and a ridge formed on the under side of the actuating plate when in such position to engage the first named plate intermediate the ends thereof.

6. A device for vibrating banjo strings comprising rigid arms to extend to the sides of and above the plane of the strings from the tail-piece end thereof toward the bridge, means for mounting said arms in rigid position, pins extending between and supported by the arms above the strings and spaced apart longitudinally of the arms, a plate mounted at one end on the pin nearest the tail-piece of the instrument and projecting toward the bridge thereof, said plate resting on the strings, and an actuating plate turnably mounted on the other pin and adapted to be swung to project toward the bridge and to then engage the first named plate, or to be swung in the opposite direction to project toward the tail-piece; and a cam member formed with the actuating plate at its axis of turning for then depressing the first named plate.

7. A structure as in claim 6, in which said cam member also serves to hold the actuating plate yieldably locked against forward swinging movement.

8. A device for vibrating banjo strings including an actuating plate, means swivelly supporting said plate from the instrument to enable the plate to be swung from a position facing the bridge of the instrument to one facing the tail-piece thereof, means enabling a depression of said plate when in its first named position to vibrate the strings, and means functioning with the swinging movement of the actuating plate from its first named to its second named position to cause said first named means to automatically increase the tension of the strings to a predetermined extent above the tension had when the actuating plate is in its first named and undepressed position.

In testimony whereof I affix my signature.
